UNITED STATES PATENT OFFICE.

BARNET NEWLAND, OF NEW YORK, N. Y.

DESIGN FOR A CANOPY FOR LIGHTING FIXTURES.

Application filed April 5, 1924. Serial No. 9,171. Term of patent 3½ years.

To all whom it may concern:

Be it known that I, BARNET NEWLAND, a citizen of the United States, and residing at New York city, in the county of New York and State of New York, have invented a new, original, and ornamental Design for Canopy for Lighting Fixtures, of which the following is a specification, reference being had to the accompanying drawings, forming part hereof.

The figures of the drawings show the design of the article.

Fig. 1 is a top view showing a quadrant with the design filled in.

Fig. 2 is a section along the lines X—X Fig. 1 to show the contour of the canopy.

I claim:

The ornamental design for a canopy for lighting fixtures, as shown.

BARNET NEWLAND.
